Specification for Design.

Patented Apr. 10, 1917.

Application filed February 10, 1917. Serial No. 147,960. Term of patent 14 years.

To all whom it may concern:

Be it known that I, GEORGE E. BALL, a citizen of the United States, residing at Stratford, in the county of Fairfield and State of Connecticut, have invented a new, original, and ornamental Design for the Body of a Teapot or other Article of Hollow Ware, of which the following is a specification, reference being had to the accompanying drawing, in which—

Figure 1 is a side elevation of the body of a teapot embodying my new design; Fig. 2 is a corresponding front view, and Fig. 3 is a horizontal section taken on the line 3—3 in Fig. 1.

I claim:

The ornamental design for the body of a teapot or other article of hollow ware, as shown.

GEORGE E. BALL.
